[57] CLAIM

The ornamental design for suspended lamp, as shown and described.

DESCRIPTION

FIG. 1 is a bottom perspective view of a suspended lamp showing my new design;

FIG. 2 is a side elevational view thereof as seen from the right hand side of FIG. 1 on an enlarged scale, the side seen from the left hand side being a mirror image; FIG. 3 is a side elevational view thereof as seen from the front of FIG. 1 on an enlarged scale, the opposite side being a mirror image;

FIG. 4 is a top plan view thereof on an enlarged scale; FIG. 5 is a bottom plan view thereof on an enlarged scale.

The broken lines are shown for illustrative purposes only.
